CLAIM

The ornamental design for an module high-bay lighting system fixture, as shown and described.

DESCRIPTION

FIG. 1 is a perspective view of an embodiment of a high-bay fixture module of the invention, the view showing a bottom of the fixture.

FIG. 2 is an exploded view of the high-bay fixture module of FIG. 1.

FIG. 3 is an exploded view of the high-bay fixture module of FIG. 1.

FIG. 4 is a bottom plan view of the high-bay fixture module of FIG. 1.

FIG. 5 is a top plan view of the high-bay fixture module of FIG. 1.

FIG. 6 is a first side view of the high-bay fixture module of FIG. 1 showing a tongue connector extending from the module for receipt in a groove of another module.

FIG. 7 is a second side view of the high-bay fixture module of FIG. 1, directly opposing the first side view of FIG. 6 and showing a groove in the module for receiving a tongue connector of another module.

FIG. 8 is a first end view of the high-bay fixture module of FIG. 1; and,

FIG. 9 is a second end view of the high-bay fixture module of FIG. 1, directly opposing the first end view of FIG. 8.
